UNITED STATES PATENT OFFICE.

MATTHEW RUSSELL BERGER, OF PHILADELPHIA, PENNSYLVANIA. •

SHANK FOR EAVES-TROUGH SUPPORTS.

Application filed February 6, 1922. Serial No. 534,311.

To all whom it may concern:

Be it known that I, MATTHEW RUSSELL BERGER, a citizen of the United States, residing at the city of Philadelphia, in the 5 county of Philadelphia and State of Pennsylvania, have invented certain new and useful Improved Shanks for Eaves-Trough Supports, of which the following is a specification.

10 This invention generally stated relates to an eaves-trough hanger and has more especial relation to a shank therefor and method of making same.

Eaves-trough hangers, sometimes called 15 gutter-hangers, as are now in common use and acceptable to the trade are of two distinct types, each of which possess disadvantageous features. One type is comprised of 20 two-part, stamped, sheet-metal shanks the parts of which are riveted together in a manner to preclude a maximum, vertical adjustment of the circles employed in conjunction therewith. In the other type, an integral structure is present which is of cast or 25 molded metal. While in the latter instance maximum, vertical adjustment of circles may be obtained, the cost of making thereof, from a manufacturer's standpoint, is more or less prohibitive due to present day problems of metal casting or molding. Another 30 disadvantage of the latter type is the presence of tangs or prongs. With these and other disadvantages in mind I have, in the present instance, designed an efficient and 35 practical shank of sheet-metal, as wrought iron, made up of two parts so fitted together that maximum, vertical adjustment of a circle may be obtained, the method of making same being novel, simple, inexpensive and 40 expeditious.

The invention consists of the improvements and method of practicing same as hereinafter described and finally claimed.

The nature, characteristic features and 45 scope of the invention will be more fully understood from the following description taken in connection with the accompanying drawings forming part hereof, and in which:

Fig. 1, is a view in side elevation of my 50 improved shank illustrating the maximum vertical adjustment as may be obtained for a circle carried thereby, and

Figs. 2 to 7, inclusive are views herein- 55 after specifically referred to in connection with the method of making such shank.

For the purpose of illustrating my invention I have shown in the accompanying drawings one form thereof and method of forming same which is at present preferred by me, since the same has been found to 60 give satisfactory and reliable results, although it is to be understood that the various instrumentalities of which my invention consists can be variously arranged and organized and that my method of formation 65 may be otherwise practiced.

In the drawings, and referring more particularly to Fig. 1, the stem 10 of the shank is of sheet metal, as wrought iron and is of conventional channel formation. Through- 70 practically its extent, vertically considered, it is apertured transversely as at 12, whereby a gutter supporting-arm or circle 13 may be adjusted thereon in a well understood manner. Adjacent the stem top and 75 rigidly secured thereto is a plate 14 which is disposed laterally with respect to the stem 10 or in other words is disposed in a plane at right angles to the vertical axis of the stem. While the plate may be of any de- 80 sired configuration, practice dictates that a rectangular form of plate is the most practical. Substantially centrally thereof the plate is penetrated by a tongue 15 extended from a side wall of the stem, the protruding 85 end of the tongue being clinched or similarly treated to rigidly fix the stem and plate together in abutting relation. The tongue 15 is in a plane at right angles to the vertical axis of the stem 10. The plate 90 14 is apertured, laterally as at 16, whereby attaching media as nails, screws or the like may be passed therethrough. It is thus apparent that the stem may be apertured, for circle accommodation, to a point closely ad- 95 jacent its top whereby adjustment of a circle may be made so that the latter may be arranged in close juxtaposition to the eaves of a building when desirable.

The method of manufacturing a shank 100 of the character stated in accordance with shop-practice as found commercially adapted therefor may be described as follows:

Channel-bar as 17, see Fig. 2, of wrought iron, which can be purchased in the open 105 market in long strips is employed for making the shank stem. Such strips are cut to desired length and apertured as at 12 see Fig. 3. Adjacent one end of the stem a side wall thereof has now stamped there- 110

from a tongue 15 see Fig. 4. This tongue is bent over so as to lie in a plane at right angles to the vertical axis of the stem. Meanwhile the plates 14 have been stamped 5 from sheet-metal and provided with a substantially central slot 18, see Fig. 5. Also the apertures 16 have been formed therein.

To assemble the above described parts it is merely necessary to position them as 10 shown in Figs. 6 and 7, with the tongue 15 projected through the slot 18 in plate 14 and the side wall of the stem from which has been stamped the tongue abutting 15 against said plate and then clinching, filing, hammering or otherwise upsetting the exposed end of the tongue to clamp the stem and plate together.

It will now be apparent that I have devised a novel and useful construction which 20 embodies the features of advantage enumerated as desirable in the statement of the invention and the above description and while I have in the present instance shown and described the preferred embodiment 25 thereof which has been found in practice to give satisfactory and reliable results, it is to be understood that the same is susceptible of modification in various particulars without departing from the spirit or scope 30 of the invention or sacrificing any of its advantages.

What I claim is:—

1. A device of the character stated comprising a stem of channel-iron apertured 35 throughout the major portion of its extent for the adjustable support of a gutter supporting-arm, a side wall of said stem adjacent its top having projected therefrom a tongue disposed in a plane at 40 right angles to the vertical axis of said stem and a plate rigidly secured below and near the stem top, said plate being pene-

trated by said tongue and being apertured for the reception of attaching means.

2. A device of the character stated comprising a stem of channel iron apertured 45 throughout the major portion of its extent for the adjustable support of a gutter supporting-arm, a side wall of said stem adjacent its top having stamped therefrom 50 a tongue disposed in a plane at right angles to the vertical axis of the stem, and a plate rigidly secured below and near the stem top, said plate being centrally slotted to receive said tongue and being apertured for 55 the reception of attaching means.

3. A device of the character stated comprising a stem of channel iron apertured 60 throughout the major portion of its extent for the adjustable support of a gutter 60 supporting-arm, attachment-plate supporting means fixed to and projected from a side wall of said channel-iron adjacent the top thereof in a plane at right angles to the vertical axis of said stem whereby the 65 gutter supporting-arm may be moved in an unobstructed manner through said channel iron for maximum vertical adjustment and an attachment-plate rigidly secured to said supporting means.

4. As a new article of manufacture a shank for an eaves-trough which shank is of channel-iron and has an unobstructed passage 70 throughout its extent and is apertured throughout the major portion of its extent, attachment-plate supporting means fixed to and projected from a side wall of 75 said shank adjacent the top thereof in a plane at right angles to the vertical axis of said shank and an attachment-plate rigidly secured to said supporting means.

In testimony whereof, I have hereunto signed my name.

MATTHEW RUSSELL BERGER.
